Inventor

Elias C. Patterson

United States Patent Office.

ELIAS C. PATTERSON, OF ROCHESTER, NEW YORK.

Letters Patent No. 79,497, dated June 30, 1868.

IMPROVEMENT IN GRAIN-SEPARATOR.

The Schedule referred to in these Letters Patent and making part of the same.

TO ALL WHOM IT MAY CONCERN:

Be it known that I, ELIAS C. PATTERSON, of Rochester, Monroe county, State of New York, have invented a new, useful, and improved Grain-Separator; and I declare that the following is a full, clear, and exact description of the same, reference being had to the accompanying drawings.

Figure 1 represents a side sectional view of my separator.

Figure 2 represents top view of the under sieve.

Figure 3 represents sectional view of the eccentrics on shaft.

Similar letters of reference in the different figures indicate the same parts of my invention.

The object of my invention is to produce a shake to the upper and lower sieves, by which the grain can be rapidly passed over, without clogging on the sieves.

To enable others skilled in the art of manufacturing and using my invention, I will describe the same.

A represents the framework of my machine. B represents the hopper, into which the grain is admitted. C represents the upper sieve. D represent under sieve. E represents the arm, by which the sieves are operated. F represents the bolt or pivot, on which the arm works. G represents the eccentric, which works the arm back and forth. H represents a wedge-shape slide upon each side of the lower sieve, which gives the sieve a side motion, at the same time it receives its end motion. I represents a hook, on the under lower end, of the under sieve, which hooks into a strap from the lower end of the arms. J represents the strap into which the hook I is attached. K represents an oblong hole in the arms, in which the eccentric works, and as the arms work upon a pivot above the eccentric, and as the length of arms is equal above and below the eccentric, it consequently gives twice the length of shake to the lower sieve than it does to the upper one. As I use zinc for the upper sieve, to take out the coarser substance, it requires a much shorter shake than the under wire sieve. L represents a pin, in the upper end of the arms, upon which the upper zinc sieve is attached.

What I claim as my invention, and desire to secure by Letters Patent, is—

1. The arms E, upon pivots F, operated by eccentric, G, and operating upper and lower sieves, substantially as described.

2. Also the wedge H on the lower sieve, for the purpose set forth.

ELIAS C. PATTERSON.
